**PITOT UNIT FOR A MARINE SPEEDOMETER
OR THE LIKE**

Howard S. Taylor, Fox River Grove, Ill., assignor to Air-guide Instrument Company, Chicago, Ill., a corporation of Illinois

Filed Oct. 25, 1961, Ser. No. 67,254

Term of patent 14 years
(Cl. D52—1)

FIG. 1 is a side elevational view of a Pitot unit for a marine speedometer, or the like, showing my new design; FIG. 2 is a top plan view thereof; FIG. 3 is a bottom plan view thereof; FIG. 4 is a left end elevational view thereof; and FIG. 5 is a right end elevational view thereof. The side of the Pitot unit opposite that shown in FIG. 1 is substantially the same in appearance as the side shown.

I claim:

The ornamental design for a Pitot unit for a marine speedometer or the like, as shown and described.
